United States Patent Office

Des. 228,970

Patented Oct. 30, 1973

228,970

CATHETER RETAINER

Charles H. Cohen and Vernon F. Leonard, Denver, Colo.,
assignors to Goldberg Plastics, Inc., Denver, Colo.

Filed Mar. 15, 1971, Ser. No. 124,647

Term of patent 14 years

Int. Cl. D24—02

U.S. Cl. D83—12 A

FIG. 1.

FIG. 2.

FIG. 3.

FIG. 4.

FIG. 1 is a top plan view of the catheter retainer showing our new design, the bottom and side views being mirror images;

FIG. 2 is a front end view thereof;

FIG. 3 is a rear end view thereof; and

FIG. 4 is a diametrical section view taken along the line 4—4 of FIG. 2.

We claim:

The ornamental design for a catheter retainer, as shown and described.
